GORDON E. ROEDDING, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

DOOR LATCH.

Application filed July 19, 1926. Serial No. 123,276.

The present invention relates to latches for refrigerator doors and the like; and its object is to provide a latch having improved means for yieldingly holding the latching bolt in certain positions, and, in certain movements of the bolt, urging the same into one of its positions; and further, to provide a latch having such means and adapted to be mounted on a door swingably carried at either of its opposite sides; and further, to provide means for holding the latching bolt of a latch thus mounted against retraction in one direction.

These and any other objects hereinafter appearing are attained by, and the invention finds preferable embodiment in, the structure hereinafter particularly described in the body of this specification and illustrated by the accompanying drawings, in which:—

Figure 1 is a front view of a latch and its keeper element;
 Figure 2 is an inner side view of the latch showing the bolt in latching position;
 Figure 3 is a like view of the same, but showing the bolt in a retracted position;
 Figure 4 is a horizontal sectional view of the same taken on line 4—4 of Figure 2; and
 Figure 5 is a left hand side view of the latch and its keeper element, showing the door member on which the latch is mounted approaching closed position.

In the embodiment of the invention illustrated by the accompanying drawings, a latch is shown mounted on the closure member 1 of a door, its keeper member 2 being mounted on the jamb or frame member 3 of the door.

In Figure 1 the latch is shown mounted on a closure member hinged at its right hand side, but the same latch may be mounted on a closure member hinged at its opposite or left-hand side. This latch comprises a latching bolt 4 swingably mounted on the pivot post 5 and enclosed in a casing 6, a portion 7 of the bolt extending through a slot 8 in the casing and being adapted to latchingly engage in the keeper or recess 9 in the element 2 to hold the closure member 1 shut, said portion 7 being desirably provided with an anti-friction roll 10. This latching bolt may be swung by hand by any suitable means or part thereof; in the illus-

trated construction however it is swung by 55 its handle arm 11 extending through an opening 12 in the casing.

In the illustrated latch capable of being mounted on the right hand side or the left hand side of a closure member, the bolt 4 has two open bearings 13, 14 spaced apart in the bolt's transverse direction. The "floating" element 15 slidably bears between the bolt 4 and the rear wall 17 of the casing and has three portions 18, 19, 20 triangularly spaced apart. Two of these portions—18, 19—removably seat in the bolt's open bearings 13, 14 respectively in the latching position of the bolt, as seen in Figure 2; but when the outer portion 7 of the bolt is moved upwardly from latching position, the portion 19 of said element turns in the bearing 14, while the other portion 18 moves out of the other bearing 13 as seen in Figure 3; and in case the latch is mounted on a door closure 75 hinged at its opposite or left hand side, the swinging of the bolt in the opposite direction to retracted position causes the portion 18 of the element 15 to turn in the bearing 13, and said element's portion 19 to move 80 out of the bearing 14.

Means are provided for urging this element 15 toward said bearings, comprising a member 21 whose spring ends 22 bear on the wall 23 of the casing and whose middle portion has a bearing 24 in which is held the third portion 20 of said element 15. As the latching bolt is swung in either direction from latching position, this portion 20 turns in the bearing 24. The spring-pressed member 21 yieldingly holds the bolt 4 in its latching engagement in the keeper and also holds the same yieldingly in either of its retracted positions; and when this bolt moves to or from its latching position and from or to either of its retracted positions it is, at a certain point in its movement, urged to the position to which it may be moving.

A detent 25 is mounted at 26 on the latching bolt pivotally and is turned as by gravity to the position seen in Figures 2 and 3 wherein its extremity 27 engages a stop 28 on the casing to prevent the outer end 7 of the bolt from being moved downwardly and the bolt from moving to that retracted position in which the bolt's handle arm 11 is elevated. This provision is made to prevent

the bolt 4 from being accidentally moved to the said retracted position when the closure member 1 is open, for, in such an accidental occurrence, the bolt retracted into the said position would strike the door jamb or frame should the closure be slammed shut and thus likely injure the parts. When this latch is mounted on a door hinged at its left hand side, the detent 25 falls by gravity to an opposite position wherein its other extremity 30 engages the opposite stop 31 to effect a like purpose.

I desire to claim this detent broadly inasmuch as it is operable in the same manner in connection with any latching bolt movable in opposite directions from latching position and being thus adaptable for mounting on a door hinged at either side. In case the latch is mounted only on doors hinged at their right hand sides or only on doors hinged at their left hand sides, one of the bearings 13 or 14 (as the case may be) does not turnably receive the corresponding portion 18 or 19 of the element 15, but constitutes merely a surface of the bolt with which said corresponding portion of the element 15 engages or abuts in the bolt's latching position.

When the closure member 1 is moved to nearly closed position, the roll 10 strikes the inclined portion 35 of the element 2, in case the latching bolt happens to be in the position seen in Figure 2, and in the further closing movement of the member 1 the roll 10 of the retracted bolt strikes the inclined portion 36 of the element 2 and is thereby moved downwardly into latching engagement in the keeper or recess 9.

The invention being intended to be pointed out in the claims, is not to be limited to or by details of construction of the particular embodiment thereof illustrated by the drawings or hereinbefore described.

I claim:

1. In combination with a keeper, a latch comprising: a bolt swingably mounted on a door member and movable to latching position in the keeper and to retracted position, and having an open bearing and a surface spaced therefrom in the bolt's transverse direction; an element having three portions one of which seats in said bearing and another of which engages said surface in the bolt's latching position, said first-mentioned portion turning said bearing in the bolt's swinging movement; means having a bearing containing the third of said portions of said element and in which it turns in the bolt's swinging movement, said means being spring-pressed to urge the two first-mentioned portions of said element into seating position in the bolt's bearing and into engagement with its said surface respectively in the bolt's latching position, and to yieldingly hold the bolt in either of its said

positions, and at a point in the bolt's movement to urge the same to the other of its said positions.

2. In combination with a keeper, a latch comprising: a bolt swingably mounted on a door member and movable to latching position in the keeper and in either direction therefrom to retracted position, and having open bearings spaced apart in the bolt's transverse direction; an element having three spaced-apart portions, two of which seat in the bolt's bearings respectively in the latching position of the bolt, and in one of said bearings one of said two portions turns in the bolt's movement to and from one of its retracted positions and in the other of said bearings the other of said two portions turns in the bolt's movement to and from the other of its retracted positions; means having a bearing containing the third of said portions of said element and in which it turns in the bolt's swinging movement, said means being spring-pressed to urge the two first-mentioned portions of said element into seating position in the bolt's bearings in the bolt's latching position, and to yieldingly hold the bolt in any of its said positions and at a point in the bolt's movement to urge the same to another of its said positions.

3. In combination with a keeper, a latch comprising: a bolt swingably mounted on a door and movable to latching position in the keeper and in either direction therefrom to retracted position, and having open bearings spaced apart in the bolt's transverse direction; an element having three spaced-apart portions, two of which seat in the bolt's bearings respectively in the latching position of the bolt, and in one of said bearings one of said two portions turns in the bolt's movement to and from one of its retracted positions and in the other of said bearings the other of said two portions turns in the bolt's movement to and from the other of its retracted positions; means having a bearing containing the third of said portions of said element and in which it turns in the bolt's swinging movement, said means being spring-pressed to urge the two first-mentioned portions of said element into seating position in the bolt's bearings in the bolt's latching position, and to yieldingly hold the bolt in any of its said positions and at a point in the bolt's movement to urge the same to another of its said positions; stops carried by said door member on the opposite sides respectively of the bolt; a detent turnable on the bolt to a position engaging one of the stops to hold the bolt against movement in one direction to retracted position, and turnable on the bolt to another position engaging the other stop to hold the bolt against movement in the other direction to retracted position.

4. In combination with a keeper, a latch

comprising: a bolt swingably mounted on a door member and movable to latching position in the keeper and in either direction therefrom to retracted position, and having open bearings spaced apart in the bolt's transverse direction; an element having three spaced-apart portions, two of which seat in the bolt's bearings respectively in the latching position of the bolt, and in one 5 of said bearings one of said two portions turns in the bolt's movement to and from one of its retracted positions and in the other of said bearings the other of said two portions turns in the bolt's movement to and from 10 the other of its retracted positions; means having a bearing containing the third of said portions of said element and in which it turns in the bolt's swinging movement, said means being spring-pressed to urge the two 15 first-mentioned portions of said element into seating position in the bolt's bearings in the bolt's latching position, and to yieldingly hold the bolt in any of its said positions and at a point in the bolt's movement to urge the 20 same to another of its said positions; stops carried by said door member on the opposite sides respectively of the bolt; a detent turnable by gravity on the bolt to a position engaging one of the stops to hold the bolt 25 against movement in one direction to retracted position, and turnable on the bolt to another position engaging the other stop to hold the bolt against movement in the other direction to retracted position.

5. In combination with a keeper, a latch comprising: a bolt swingably mounted on a door member and movable to latching position in the keeper and in either direction therefrom to retracted position; stops carried by said door member on the opposite sides respectively of the bolt; a detent turnable on the bolt to a position engaging one 30 of the stops to hold the bolt against movement in one direction to retracted position, and turnable on the bolt to another position engaging the other stop to hold the bolt against movement in the other direction to retracted position.

6. In combination with a keeper, a latch comprising: a bolt swingably mounted on a door member and movable to latching position in the keeper and in either direction therefrom to retracted position; stops carried by said door member on the opposite 35 sides respectively of the bolt; a detent turnable by gravity on the bolt to a position engaging one of the stops to hold the bolt

against movement in one direction to retracted position, and turnable on the bolt to another position engaging the other stop to hold the bolt against movement in the other direction to retracted position.

7. In combination with a keeper, a latch comprising: a bolt swingably mounted on a door member and movable to latching position in the keeper and to retracted position, and having an open bearing and a surface spaced therefrom in the bolt's transverse direction; an element having three portions one of which seats in said bearing and another of which engages said surface in the bolt's latching position, said first-mentioned portion turning in said bearing in the bolt's swinging movement; means having a bearing containing the third of said portions of 40 said element and in which it turns in the bolt's swinging movement, said means being spring-pressed to urge the two first-mentioned portions of said element into seating position in the bolt's bearing and into engagement with its said surface respectively in the bolt's latching position, and to yieldingly hold the bolt in either of its said positions.

8. In combination with a keeper, a latch comprising: a bolt swingably mounted on a door member and movable to latching position in the keeper and in either direction therefrom to retracted position, and having open bearings spaced apart in the bolt's transverse direction; an element having three spaced-apart portions, two of which seat in the bolt's bearings respectively in the latching position of the bolt, and in one of said bearings one of said two portions turns in the bolt's movement to and from one of its retracted positions and in the other of said bearings the other of said two portions turns in the bolt's movement to and from the other of its retracted positions; means having a bearing containing the third of said portions of said element and in which it turns in the bolt's swinging movement, said means being spring-pressed to urge the two first-mentioned portions of said element into seating position in the bolt's bearings in the bolt's latching position, and to yieldingly hold the bolt in any of its said positions.

In testimony whereof I have hereunto set my hand at Grand Rapids, Michigan, this 15th day of July, 1926.

GORDON E. ROEDDING.
